DESIGN FOR A GAME BOARD

William Grant Williams, Anaheim, Calif.

Application January 30, 1945, Serial No. 117,677

Term of patent 7 years

(Cl. D34—5)

To all whom it may concern:

Be it known that I, William Grant Williams, a citizen of the United States, residing at Anaheim, in the county of Orange and State of California, have invented a new, original, and ornamental Design for Game Board, of which the following is a specification, reference being had to the accompanying drawing, forming part thereof, wherein

Fig. 1 is a top plan view of the game board embodying my new design; and Fig. 2 is a vertical section taken substantially upon the line 2—2 upon Fig. 1.

I claim:

The ornamental design for a game board, as shown.

WILLIAM GRANT WILLIAMS.
